(57) CLAIM

The ornamental design for a headrest cover, as shown and described.

DESCRIPTION

FIG. 1 is a perspective view of a headrest cover;

The broken lines in FIG. 1 are for illustrative purposes only and form no part of the claimed design.

FIG. 2 is a front elevation thereof;

FIG. 3 is a rear elevation thereof;

FIG. 4 is a left side elevation thereof;

FIG. 5 is a right side elevation thereof;

FIG. 6 is a top plan view thereof;

FIG. 7 is a bottom view thereof;

The broken lines in FIGS. 6 and 7 are for illustrative purposes only and form no part of the claimed design.

FIG. 8 is showing a front elevation view of a headrest in a position of use; and,

FIG. 9 is showing a rear elevation view of a headrest in a position of use.

The broken lines in FIGS. 8 through 9 are for illustrative purposes only and form no part of the claimed design.
